UNITED STATES PATENT OFFICE

2,585,074

CARTON SETUP MACHINE

Lawrence E. Arneson, Morris, Ill., assignor to
 Morris Paper Mills, Chicago, Ill., a corporation
 of Illinois

Application July 12, 1947, Serial No. 760,540

12 Claims. (Cl. 93—53)

1

This invention has to do with a novel type of machine for setting up cartons. More particularly, it pertains to a machine for setting up collapsed cartons of the bottle carrying type by folding the side wall sections and manipulating the end panels along predetermined lines of fold in order to maintain the carton in set-up and locked position.

Generally, it is an object of the invention to provide mechanism for holding a side wall portion of such cartons downwardly in a fixed position in order to be able to open the cartons, mechanism for thereafter opening the cartons by folding the remaining wall sections along fold lines adjacent the ends of the wall of the carton which is held down in fixed position, and mechanism for manipulating the end wall panels for maintaining the cartons in opened and interlocked set-up position.

More specifically, it is an object of the invention to provide a machine as above described in which there is included oppositely disposed movable hold down fingers to hold down a side wall of the carton in fixed position to permit folding and manipulating of the remaining bottom and side wall portions of the carton in order to open the same, folding arms or members adapted to engage the bottom panel of the carton and to fold the same around predetermined lines of fold adjacent the ends of the held down side wall panel in such a manner as completely to open the carton, and end panel tucking and locking fingers for forming the end walls of the carton and to bring the same in interlocked position so that the carton will be maintained in an open, erect and upright position for the reception of the goods which they are adapted to receive.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a transverse end elevational view, partly in section, of a machine embodying the present invention;

Fig. 2 is a top plan view of the machine depicted in Fig. 1 but only half of which is nec-

2

essarily shown since the side of the machine opposite the center line is substantially identical therewith;

Fig. 3 is a front elevational view, partly in section, looking from right to left of the machine depicted in Fig. 1, taken along the line 3—3 and looking in the direction of the arrows;

Fig. 4 is a plan view of one of two oppositely disposed side wall panel hold down mechanisms;

Fig. 5 is a perspective view of the carton panel folding and opening mechanism showing only one of the folding arms;

Fig. 6 is a plan view, partly in section, showing a detail of the mechanism for inwardly tucking panel portions of the end walls;

Fig. 7 is a perspective view of detailed portions of one of the oppositely disposed devices for folding and manipulating the remaining panel sections of the end wall and for bringing the same into interlocking engagement with the top of the carton to hold the same in erect, opened and set-up position;

Fig. 8 is a plan view of a collapsed carton illustrating the operation of the panel hold down mechanism;

Fig. 9 is a plan view showing the carton after it has been opened by folding it along fold lines adjacent the ends of the held down panel, and the mechanism for simultaneously inwardly tucking opposite panel sections of the end walls;

Fig. 9a is a view in longitudinal section along a line corresponding generally to line 9a—9a of Fig. 9;

Fig. 10 illustrates the completion of the operation of setting-up of the carton and the mechanism for manipulating the remaining panel sections of the end walls to bring them into interlocked position to hold the carton erect and opened;

Fig. 11 is a fragmentary portion of the top corner of the carton showing the manner in which slotted sections of opposite end walls interlocking engage the downwardly directed ridge piece of such a carton which occurs during the completion of the operation depicted in Fig. 10; and

Fig. 12 is a perspective view of the completed carton set up in interlocked position ready for the reception of such commodities, for example, as beverage bottles.

The type of carton especially adapted to be handled by this machine is that more particularly disclosed in Patent No. 2,345,568 commonly used as a carrying carton for well known bottled beverages.

Referring more particularly to the drawings,

there is shown a bed plate indicated generally at 10 and suitably connected to the sides of the machine for receiving collapsed cartons with handles inserted therein. On each side of the bed plate two shafts 11, 11 are held in vertical position. Since the various mechanisms and other structure operating upon and in conjunction with these shafts are the same on both sides of the center line, as heretofore indicated, it is not deemed necessary to repeat the description and operation, but like parts will be referred to by like numbers. At the bottom end of each shaft 11 is a miter gear 12 which is meshed with a miter gear 13 on a main drive shaft 14. This drive shaft 14 is rotated in any suitable manner from a drive gear or wheel member 15 at one end of the shaft and from any suitable source of power.

Attached toward the upper end of each vertical shaft 11 is a cam member 16 (see Figs. 4 and 8). The rotation of the shaft 11 rotates the camming elements 16, and these in turn operate the carton hold down finger mechanism. This finger mechanism preferably consists of a generally triangularly shaped member 17 which is pivotally mounted at 18 on the frame of the machine adjacent the bed plate 10. At one end of the triangular member 17 is a cam roller which follows the cam member 16 by which it is actuated. At an opposite end of the triangular member is a spring 19 secured to the frame of the machine so that the triangular member can be spring retracted. Each triangularly shaped member 17 has a slight projection 20 at its spring controlled end and this is the finger which is adapted to enter between the side walls of the carton to hold one of the walls in fixed position against the bed plate 10.

After a collapsed carton has been passed onto the bed plate 10 and held down as above described, the same is ready to be opened by folding the remaining wall sections, including the base or bottom panel, along fold lines at each end of the side walls.

Referring to Figs. 8 and 12, it will be understood that fold lines appear at each end of the collapsed carton, that is, at 21, along a line paralleling the ridge 23 of the ultimately erected carton, and at 22 along the base of the uppermost side wall. The fold line which defines the base of the other, lower side wall is indicated at 24.

The carton opening mechanism is constituted by a pair of actuating arms 25 mounted upon a shaft 26 journaled in the side frames of the machine, somewhat below but in parallel arrangement with the main drive shaft 14. At the upper end of each arm is a gear segment 27 meshed with a mitered gear 28 suitably journaled in the frame of the machine. Each gear 28 has secured thereto an extension folding arm 29 with a raised shoulder 30 against which the leading edge of the carton abuts as it is fed into the machine along the bed plate 10. Actually, these folding or carton opening arms 29 are pivotally mounted in spaced apart position in such a manner that they will receive, for example, the bottom panel or base of the carton as it is moved along the base plate and against the abutting shoulders 30. It is at this moment that the above described hold down members 17 secure the collapsed carton to the bed plate.

Simultaneously with this action the folding arms 29 swing upwardly through an angle of 90° and somewhat therebeyond, as illustrated in Fig. 1 in dotted line position, and in so doing, raise or swing the base of the carton so as to open it by

folding the various connected panels along the fold lines 21, 22, 23 and 24. This pivotal movement of the arms 29 is imparted thereto by the actuating arm 25 having the gear segment 27 thereon. The arm 25 in turn is actuated by the rotation of the main drive shaft because of the connecting structure between it and the shaft 26. For example, in the center of the shaft 26 there is secured an extension arm 31 carrying a cam roller or follower 32. This arm is drawn in the direction of the drive shaft 14 by means of a spring 33 attached to a base extension 34 of the machine. The spring 33 holds the cam roller 32 against an actuating cam 35 on the shaft 14. It will readily be seen that the movement of the cam 35 contacting the cam follower 32 actuates the arm 31 which in turn oscillates the shaft 26. The shaft 26 carrying the actuating arms 25 pivotally swings the folding arms 29 through and beyond the 90° above mentioned.

Looking down upon the opened carton now lying on the side wall which is held down against the bed plate, as shown in Fig. 9, both the side walls and base or bottom of the carton now can be seen. Also, the openings in the carton for the reception of such commodities as the bottles heretofore mentioned permit the position of some of the panel sections of the end walls to be seen. It is necessary first to inwardly and upwardly tuck the uppermost pair of panel sections of the end walls toward the uppermost side wall. For convenience these panel sections are numbered 36. The tucking-in operation is accomplished by means of the tucking mechanisms indicated generally at 37 (see Figs. 6 and 9) and this mechanism functions in this respect approximately simultaneously with the operation of the opening of the carton by means of the arms 29.

The above mentioned panel tucking mechanisms are operated by the same shafts 11 which operate the mechanism for holding down the side wall of the carton. That is, there are also secured on the shafts 11 cam members 38. Suspended adjacent these cam members are tucking rods or fingers 39 for inwardly and upwardly tucking the panel sections 36. These fingers 39 preferably are pivotally suspended as at 40 by suitably securing them in the top of the machine frame.

It is next necessary upwardly and outwardly to fold the remaining oppositely disposed end wall panel sections which are designated on the drawings as 41. This is accomplished by the locking panel and tucking mechanism somewhat diagrammatically depicted in Fig. 7. A tucking and locking member, for manipulating each panel 41, is indicated generally at 42 and is moved in the direction of the arc indicated by the arrow in Fig. 7. This member is pivotally mounted on a shaft 43 and is held in a downward position by a counterweight 44 also mounted on the shaft 43. Disposed beneath the counterweight and mounted to slide in a slot 45 formed by the gibs 46 and 47 is a T-shaped member 48 carrying a cam roller 49. This cam roller rides the edge surface of a cam 50 which is mounted on the drive shaft 14. The tucking and locking members 42 move upwardly through side recesses in bed plate 10 and strike the panels 41 from below as viewed in the drawings. In doing this they pass through the bottle receiving openings in the lower side wall of the carton. This action occurs, of course, after the hold down fingers 17 have moved out of operative position. The hold down fingers are no longer necessary in any

event inasmuch as the folding arms 29 now securely hold the carton downwardly against the bed plate to permit completion of the manipulating of the end panel sections 41 of the remaining carton end wall portions.

The carton end walls are interlocked as shown more clearly in Fig. 11. Locking action takes place by having the locking members 42 manipulate the panel sections 41 (see Figs. 10 and 11) in such a manner that a locking tab 51, provided by a notch in the panel 41, straddles the glue flap or ridge piece 52 immediately beneath the ridge along the top of the carton. This locking action serves to hold the carton in set-up interlocked position as shown in Fig. 12.

It will be appreciated that certain changes may be made in the above construction and different embodiments of the invention could be made without departing from the scope thereof, hence, it is intended that all matter contained in the above description or shown in the accompanying drawings shall be interpreted as illustrative and not in a limiting sense.

Having described my invention what I claim as new and desire to secure by Letters Patent is:

1. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism for holding a portion of one side wall of the carton in fixed position, mechanism for opening the carton by folding the other side wall and bottom about said first named and further fold lines, and mechanism for manipulating the folded end wall panels to opened and interlocked set-up position at a right angle to said side walls, said last named mechanism including means acting on a portion of said end wall panel to urge the same in a direction outwardly of the carton.

2. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism including a pivotally mounted hold down finger for holding a portion of one side wall of the carton in fixed position, mechanism for opening the carton by folding the other side wall and bottom about said first named and further fold lines, and mechanism for manipulating the folded end wall panels of the carton to opened and interlocked set-up position at a right angle to said side walls, said last named mechanism including means acting on a portion of said end wall panels to urge the same in a direction outwardly of the carton.

3. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism including oppositely disposed and pivotally mounted, cam actuated hold down fingers for holding a portion of one side wall of the carton in fixed position, mechanism for opening the carton by fold-

ing the other side wall and bottom about said first named and further fold lines, and mechanism for manipulating the folded end wall panels of the carton to opened and interlocked set-up position at a right angle to said side walls, said last named mechanism including means acting on a portion of said end wall panels to urge the same in a direction outwardly of the carton.

4. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism including a pair of pivotally mounted, spring retracted hold down fingers, for holding a portion of one side wall of the carton in fixed position, mechanism for opening the carton by folding the other side wall and bottom about said first named and further fold lines, and mechanism for manipulating the folded end wall panels to opened and interlocked set-up position at a right angle to said side walls, said last named mechanism including means acting on a portion of said end wall panels to urge the same in a direction outwardly of the carton.

5. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton which comprises, in combination, mechanism for holding a portion of one side wall of the carton in fixed position, mechanism including a pivotally mounted carton bottom folding member, for opening the carton by folding the other side wall and bottom about said first named and further fold lines, and mechanism for manipulating the folded end wall panels to opened and interlocked set-up position at a right angle to said side walls, said last named mechanism including means acting on a portion of said end wall panels to urge the same in a direction outwardly of the carton.

6. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism for holding a portion of one side wall of the carton in fixed position, mechanism including pivotally mounted and cam actuated carton panel manipulating arms for opening the carton by folding the other side wall and bottom about said first named and further fold lines, and mechanism for manipulating the folded end wall panels to opened and interlocked set-up position at a right angle to said side walls, said last named mechanism including means acting on a portion of said end wall panels to urge the same in a direction outwardly of the carton.

7. A machine for setting up collapsed cartons characterized by a pair of opposed side walls connected by a fold line a bottom extending between and hinged to said side walls on further fold lines, and end wall panels hinged to and folded between said side walls in the collapsed, knock-down condition of the carton, which comprises, in combination, mechanism for holding a portion of one side wall of the carton in fixed po-

sition, mechanism including cam actuated and spring retracted carton bottom folding members, for opening the carton by folding the other side wall and bottom about said first named and further fold lines, and mechanism for manipulating the folded end wall panels to opened and interlocked set-up position at a right angle to said side walls, said last named mechanism including means acting on a portion of said end wall panels to urge the same in a direction outwardly of the 10 carton.

8. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises in combination, mechanism for holding a portion of one side wall of the carton in fixed position, mechanism for opening the carton by folding the other side wall and bottom about said first named and further fold lines, and mechanism including oppositely disposed end panel tucking members for manipulating the folded end wall panels to opened and interlocked set-up position at a right angle to said side walls, said last named mechanism including means acting on a portion of said end wall panels to urge the same in a direction outwardly of the carton.

9. A machine for setting up collapsed cartons characterized by a pair of opposed side walls connected by a fold line, a bottom extending between and hinged to said side walls on further fold lines and end wall panels hinged to and folded between said side walls in the collapsed, knock-down condition of the carton, which comprises, in combination, mechanism for holding a portion of one side wall of the carton in fixed position, mechanism for opening the carton by folding the other side wall and bottom about said first named and further fold lines, and mechanism including cam actuated end panel tucking fingers for manipulating the folded end wall panels to opened and interlocked set-up position at a right angle to said side walls, said last named mechanism including means acting on a portion of said end wall panels to urge the same in a direction outwardly of the carton.

10. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism for holding a portion of one side wall of the carton in fixed position, mechanism for opening the carton by

5 folding the other side wall and bottom about said first named and further fold lines, and mechanism including pivotally mounted panel locking members for manipulating the folded end wall panels to opened and interlocked set-up position at a right angle to said side walls, said last named mechanism including means acting on a portion of said end wall panels to urge the same in a direction outwardly of the carton.

11. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism for holding a portion of one side wall of the carton in fixed position, mechanism for opening the carton by folding the other side wall and bottom about said first named and further fold lines, and mechanism including cam actuated and counterweighted panel locking members for manipulating the folded end wall panels to opened and interlocked set-up position at a right angle to said side walls, said last named mechanism including means acting on a portion of said end wall panels to urge the same in a direction outwardly of the carton.

12. A machine for setting up collapsed cartons characterized by a pair of opposed side walls connected by a fold line, a bottom extending between and hinged to said side walls on further fold lines, and end wall panels hinged to and folded between said side walls in the collapsed, knock-down condition of the carton, which comprises, in combination, mechanism including a pivotally mounted hold down finger, for holding a portion of one side wall of the carton in fixed position, mechanism including pivotally mounted carton bottom folding members for opening the carton by folding the other side wall and bottom about said first named and further fold lines, mechanism including oppositely disposed finger members and pivotally mounted panel locking members for manipulating the end wall panels to opened and locked position at a right angle to said side walls, said last named mechanism including means acting on a portion of said end wall panels to urge the same in a direction outwardly of the carton.
